[57] CLAIM

The ornamental design of an operator handle, as shown and described.

DESCRIPTION

FIG. 1 is a perspective view of the operator handle in an operative position relative to an exemplary operator cover and window frame partially shown in phantom;

FIG. 2 is a top view of the operator handle;

FIG. 3 is a left side view of the operator handle, the side opposite being a mirror image;

FIG. 4 is a front view of the operator handle;

FIG. 5 is a bottom view of the operator handle; and,

FIG. 6 is a rear view of the operator handle.

The broken lines in FIGS. 5 and 6 surround interior surfaces of the handle design which do not form a portion of the claimed design.
